DESIGN FOR A STOVE.

Design No. 13,605, dated February 13, 1883.

UNITED STATES PATENT OFFICE.

H. CLAY BASCOM AND FRANCIS RITCHIE, OF TROY, NEW YORK, ASSIGNEES
TO GEORGE W. GILL, OF COLUMBUS, OHIO.

DESIGN FOR A STOVE.

SPECIFICATION forming part of Design No. 13,605, dated February 13, 1883.

Application filed December 30, 1882. Term of patent 14 years.

To all whom it may concern:

Be it known that we, H. CLAY BASCOM and FRANCIS RITCHIE, citizens of the United States, residing in the city of Troy, in the county of Rensselaer and State of New York, have jointly invented and produced a new and original Design for Stoves, of which the following is a specification, reference being had to the accompanying cut, print, or engraving, 10 representing said new design.

The design for the stove-body consists of the top section, A, front portion, B, and end part, C, all shaped, ornamented, and arranged together so as to present substantially the 15 same appearance as is represented in the aforesaid engraving.

The design for the top section, A, consists of the open-work cap-piece D, in connection with the top plate, E, all shaped, ornamented, 20 and arranged together so as to appear substantially as shown in the aforesaid cut.

The design for the cap-piece D consists of the oblong quadrilateral base-fillet a, upwardly-tapering and concavely-curved open-work ends 25 b, and upwardly - tapering and concavely-curved sides c, composed of the united angular and curved open-work ornamentation d in the quadrilateral middle portion, and the radial open-work figures e in the triangular end parts, 30 all shaped and arranged together substantially as shown in the aforesaid print.

The design for the top plate, E, consists of the oblong quadrilateral base-fillet f and the upwardly and inwardly inclined part g, having 35 the series of oblong end-pointed ornaments h and the centrally-contracted ornaments i, alternating with the ornaments h, all shaped and disposed together substantially as shown in the aforesaid cut.

The design for the stove-front B consists of the four doors F, the lateral panels G, and the intermediate tablet-plate, H, all shaped, ornamented, and arranged together so as to present substantially the same appearance as is 45 represented in the aforesaid engraving.

The design for the doors F consists of the connected fan-shaped outer corner ornaments j, the central compound ornament, k, and the intervening curved - line ornamentation, l, all

shaped and arranged together substantially as 50 shown in the aforesaid print.

The design for the panels G consists of the central rosette, m, picket ornaments n at the top and bottom, and intermediate connecting linear ornaments, o, all shaped and arranged 55 substantially as shown in the aforesaid cut.

The design for the end portion, C, consists of the plate K, laterally-projecting part I, having the upwardly-tapering top p and the panel q, formed with outer convex moldings, r, and 60 inner ornamentations, s, all shaped and arranged together substantially as represented in the aforesaid engraving.

The design for the segmental skirting J consists of the lower ornamental edging, t, middle 65 bottom ornament, u, and spreading connected scroll ornaments v, all shaped and arranged together, substantially as shown in the aforesaid print, with or without the extensions w at the ends. 70

The design for the legs consists of the compound central ornament, x, upper zigzag ornamentation, y, and lateral downwardly-extended and connected linear ornaments z z', all shaped and arranged together as represented in the 75 aforesaid engraving.

What we claim as our joint invention is—

1. The design for the stove-body, composed of the parts A B C, all shaped, ornamented, and arranged together as set forth. 80

2. The design for the top section, A, composed of the parts D and E, shaped, ornamented, and arranged together as described.

3. The design for the cap-piece D, consisting of the parts a b c d e, all shaped and arranged 85 together as set forth.

4. The design for the top plate, E, consisting of the parts f g h i, all shaped and arranged together as set forth.

5. The design for the stove-front, composed 90 of the parts F G H, all shaped, ornamented, and arranged together as described.

6. The design for the doors F, consisting of the parts j k l, all shaped and arranged together as described. 95

7. The design for the panels G, consisting of the parts m n o, all shaped and arranged together as set forth.

8. The design for the end portion, C, composed of the parts K, I p q r s, all shaped and arranged together as described.

9. The design for the segmental skirting J, consisting of the ornamental parts t u v, all shaped and arranged together as set forth.

10. The design for the legs, composed of the parts x y z z', all shaped and arranged together as described.

In testimony whereof we hereunto set our hands, in the presence of two subscribing witnesses, this 12th day of December, 1882.

H. CLAY BASCOM.
FRANCIS RITCHIE.
